UNITED STATES PATENT OFFICE.

BERNARD J. KEATING, OF KEARNY, NEW JERSEY, ASSIGNOR TO DRESSEL RAILWAY.
LAMP & SIGNAL COMPANY, OF ARLINGTON, NEW JERSEY, A CORPORATION OF
DELAWARE.

SIGNAL LAMP.

Application filed March 2, 1925. Serial No. 12,481.

My invention relates to improvements in signal lamps, and the same has for its object to provide a signal lamp adapted more particularly for use as a "tail" lamp to be carried at the rear end of a locomotive, car or train, or for use as a "classification" lamp to be carried at the front of a car, locomotive or train.

Further, said invention has for its object 10 to provide a simple, efficient and reliable lamp of the character specified in which the parts thereof may be readily assembled for use, or separated for inspection or repairs, and in which said parts may be readily positioned 15 so that a given light may be displayed along the line.

Further, said invention has for its object to provide a lamp of the character specified in which the several parts thereof are so constructed and arranged that when the same 20 are united they will form a wind and weather-proof structure.

Further, said invention has for its object to provide a lamp of the character specified 25 consisting essentially of a lantern body and a base and having a supporting bracket permanently connected to the base member upon which the lantern body is rotatably disposed so that the same may be adjusted to any one 30 of a plurality of positions to display a given light.

Further, said invention has for its object to provide a lamp of the character specified which consists of two enclosing parts having 35 portions adapted to interengage to maintain the parts against separation when assembled, and to permit of the relative rotation of the parts so that the top part may be positioned to display any of a plurality of signal lights.

Further said invention has for its object 40 to provide a lamp of the character specified in which the base member may be rigidly supported in position, and the lantern body rotatably mounted upon said base so as to 45 permit of the ready and convenient adjustment and securement of the lantern body to a plurality of signal displaying positions thereon.

Other objects will in part be obvious and 50 in part be pointed out hereinafter.

To the attainment of the aforesaid objects and ends my invention consists in the novel details of construction, and in the combina-

tion, connection and arrangement of parts hereinafter more fully described and then 53 pointed out in the claims.

In the accompanying drawing showing an illustrative embodiment of the invention—

Figure 1 is an elevation of one form of lamp constructed according to and embodying my said invention;

Fig. 2 is an elevation thereof partly in section;

Fig. 3 is an elevation thereof with the upper and lower parts thereof shown separated;

Fig. 4 is a bottom plan of the upper member, and

Fig. 5 is a top plan of the lower member.

In said drawings the signal lamp is shown as consisting essentially of a base member 70 10, and a separate top member or lantern body 19 which is revolubly secured to and supported upon said base 10.

The base member 10 is preferably in the form of a relatively shallow circular receptacle having a raised bottom 10^a, and vertical wall terminating at its upper edge in an outwardly projecting ledge or rim 18.

To support the lamp, as a whole, in position upon a fixed support, the base member 80 10 is provided with a laterally extending arm 16 having an attaching bracket 17 at its outer end. By preference the said arm and bracket are formed integral with said base member 10.

The top member or lantern body 19 is hollow, and substantially spherical in form and provided in its sides with a plurality of openings in which are secured signal lights or lenses 20, 21, 22, 23, of different colors to 90 meet the requirements of the railroad or other purpose in connection with which the lamp is used. The number of signal lights is unimportant and may be varied to meet any given condition.

The open lower portion of said lantern body 19 terminates in a depending annular flange or wall portion 25 adapted to fully receive and enclose the upper portion of the base 10. The flange 25 is provided upon its 100 inner upper edge with an inwardly extending annular shoulder 26 which is adapted to rest upon the upper surface of the outwardly projecting ledge or rim 18, and to ride thereon when said lantern body is rotated relatively to 105 said base. The ledge or rim 18 also serves as a

spacing member to maintain the wall portions of the parts 10 and 19 separated in concentrically spaced relation. When the parts 10, 19 are duly assembled the line of jointure 5 of said parts will be well within, and be protected by the depending flange 25 which serves as a protecting apron in rendering the lamp wind and weatherproof.

To hold the base member 10 and body portion 19 duly connected, and to allow of the rotation of said body portion upon said base member, the depending flange 25 of the body portion 19 is provided upon its inner side, in spaced relation to the shoulder 26, with inwardly projecting lugs 27, 27 adapted to engage with the underside of the ledge or rim 18 of the base member 10. The flange 25 is also provided, intermediate said lugs 27, 27, with a similar but smaller lug 28 which is 15 adapted to be received by the recess 29 in the ledge or rim 18 of the base member 10, and, after partial rotation, to engage with the underside of the ledge or rim 18 of the base member. The lugs 27, 28 are preferably 20 formed integral with the flange 25.

In order to hold the lantern body 19 to any one adjusted position substantially ninety degrees apart, upon the base member 10 to display any one of the four signal lights, the lantern body is provided at its flange 25 with a radially extending casing 31 in which is disposed a normally projected spring-pressed plunger or pin 30 having a head 30^a at its outer end. The normally projected end of 30 said member 30 is adapted to engage with any of four recesses 32 provided in the wall of said base member 10, directly below the ledge or rim 18 thereof. The number of said recesses, in any case, corresponding with the 35 number of signal lenses mounted in the lantern body.

The illuminating medium may be of any type. In the present instance the same is shown as of the electrically operated type, 40 and to that end the base member 10 is provided with a socket 11, to receive an electric lamp 12. The current is supplied by conductors which pass through a compressible packing 13^a disposed in a stuffing box 13 in 45 the bottom of the base member 10. The lamp 12 is controlled by a switch actuating member 14 which also passes through said bottom.

The manner of operation of the signal lamp 50 will be largely obvious from the foregoing description. It need merely be noted that to adjust the lantern body 19, to display any one of the signal lenses mounted therein, the spring-pressed plunger or pin 30 is first 55 drawn outwardly to release the inner end thereof from its engagement with the recess 32 of the base. The lantern body may then be rotated upon the base, and when the same is caused to assume the desired position the 60 inner end of the plunger 30 will automatical- 65

ly enter the appropriate recess 32 necessary to hold the lantern body to the position required to display the desired signal light.

To detach the base member 10 from the lantern body 19 it merely becomes necessary 70 to first release the locking plunger 30, and then rotate the lantern body 19 until the lug 28 is brought into register with the recess 29 in the ledge or rim 18 of the base member, whereupon the lantern body may be tilted 75 and released of its engagement with the base.

It is to be noted particularly that by means of my invention I am enabled to provide a signal lamp consisting of but two essential parts which may be easily and conveniently 80 joined together or separated. As a result of the construction and arrangement of said parts, the providing the base member 10 with means rigidly supporting the entire signal lamp permits of the ready adjustment or 85 rotation of the entire lantern body with respect to said base member when changes in the signal lights are to be made.

Having thus described my said invention what I claim and desire to secure by Letters 90 Patent is:

1. A signal lamp comprising a base member, an annular wall portion extending upwardly therefrom, a horizontal shoulder extending outwardly from the upper edge thereof, and a separate lantern body, a depending annular vertical wall portion on said lantern body, a laterally projecting shoulder extending inwardly from the upper inner end of said depending wall portion, and adapted to 95 engage with the upper edge of the wall portion of said base member with the shoulder thereof engaging the depending wall portion of said lantern body whereby to maintain said vertical wall portions in spaced relation to one another, and means for securing said base member and said lantern body together, substantially as specified.

2. A signal lamp comprising a receptacle open at its upper end constituting a base member, an outwardly projecting ledge along the open end thereof, a separate lantern body having an open portion adapted to receive said base member, a shoulder within said open portion of said lantern body adapted to engage the upper portion of said ledge, and lugs within said open portion arranged in spaced relation to said shoulder and adapted to extend below said ledge; said ledge having a recess therein to permit of the inter-engagement of said base member and said lantern body for rotation relative to each other, substantially as specified.

3. A signal lamp comprising a receptacle open at its upper end and constituting a base member, a supporting bracket projecting laterally therefrom, an outwardly projecting ledge along the open end of said base member, a separate lantern body, a plurality of signal lights therein, a flange depending from said 125

- lantern body adapted to receive said base member, a shoulder within said depending flange adapted to engage said ledge, lugs within the depending flange of said lantern body arranged in spaced relation to said shoulder and adapted to extend below said ledge; said ledge having a recess therein to permit of the interengagement of said base member and said lantern body for rotation relative to each other, a locking device on said lantern body, and a plurality or recesses around said base member corresponding to the signal lights of the lantern body and adapted to receive said locking device for locking said lantern body in each of a plurality of different positions, substantially as specified.
4. A signal lamp comprising a hollow base member having an opening at the top, and a hollow upper member having an opening at the base and jointly forming a lantern casting for receiving illuminating means; said base member including an upwardly extending annular portion having a ledge extending outwardly from the upper edge thereof, and said upper member including a portion extending laterally from said opening in the base thereof and engaging said ledge, and an annular portion extending downwardly from the laterally extending portion of said upper member and engaged by said ledge to maintain said annular portions in spaced relation to one another, and lugs on the inner side of the outer of said annular portions arranged in spaced relation to the laterally extending portion of said upper member and adapted to extend below said ledge; said ledge having a recess therein to permit of the interengagement of said base member and said upper member for rotation relative to each other, 40 substantially as specified.
5. A signal lamp comprising a hollow base member having an opening at the top, and a hollow upper member having an opening at the base and jointly forming a lantern casting for receiving illuminating means; said base member including an upwardly extending annular portion having a ledge extending outwardly from the upper edge thereof, and said upper member including a portion 45 extending laterally from said opening in the base thereof and engaging said ledge, and an annular portion extending downwardly from the laterally extending portion of said upper member and surrounding the annular portion of said base member, means on the outer of said annular portions adapted to engage said ledge to retain said members together for rotation relative to each other, a locking device on the outer of said annular portions, and a plurality of means arranged around the inner of said annular portions below said ledge and adapted to receive said locking device for locking said upper member in each of a plurality of different 50 positions, substantially as specified.
6. A signal lamp comprising a hollow base member having an opening at the top, and a hollow upper member having an opening at the base and jointly forming a lantern casting for receiving illuminating means; said base member including an upwardly extending annular portion having a ledge extending outwardly from the upper edge thereof, and said upper member including a portion 55 extending laterally from said opening in the base thereof and engaging said ledge, and an annular portion extending downwardly from the laterally extending portion of said upper member and surrounding the annular portion of said base member, means on the outer of said annular portions adapted to engage said ledge to retain said members together for rotation relative to each other, a locking device on the outer of said annular portions, and a plurality of means arranged around the inner of said annular portions below said ledge and adapted to receive said locking device for locking said upper member in each of a plurality of different 60 positions, substantially as specified.
7. A signal lamp comprising a hollow base member having an opening at the top, and a hollow upper member having an opening at the base and jointly forming a lantern casting for receiving illuminating means; said base member including an upwardly extending annular portion having a ledge extending outwardly from the upper edge thereof, and said upper member including a portion 65 extending laterally from said opening in the base thereof and engaging said ledge, and an annular portion extending downwardly from the laterally extending portion of said upper member and surrounding the annular portion of said base member, means on the outer of said annular portions adapted to engage said ledge to retain said members together for rotation relative to each other, a locking device on the outer of said annular portions, and a plurality of means arranged around the inner of said annular portions below said ledge and adapted to receive said locking device for locking said upper member in each of a plurality of different positions, substantially as specified.

Signed at the city of New York, in the county and State of New York, this 2nd day of February, one thousand nine hundred and twenty-five.

BERNARD J. KEATING.
